UNITED STATES PATENT OFFICE.

RUDOLF AUGUST SCHIMANSKI, OF SPOKANE, WASHINGTON.

CLOTHES-DRIER.

1,126,575.

Specification of Letters Patent.

Patented Jan. 26, 1915.

Application filed April 14, 1913. Serial No. 761,020.

To all whom it may concern:

Be it known that I, RUDOLF AUGUST SCHIMANSKI, a citizen of the United States, residing at Spokane, in the county of Spokane and State of Washington, have invented certain new and useful Improvements in Clothes-Driers; and I do hereby declare the following to be a full, clear, and exact description of the invention, such as will enable others skilled in the art to which it appertains to make and use the same.

This invention relates to clothes racks and has particular reference to that type of such devices employed in drying clothing.

As its principal object this invention aims to provide a clothes rack of the suspended type constructed with such regard to proportion, arrangement and number of parts that it may be readily attached to the ceiling of a room and may be manipulated to be drawn up and out of the way when it is not in use, and may be lowered at other times for the purpose of hanging clothes on the rack.

A still further object of this invention is to simplify the structure of devices of the character above described so that they may be cheaply manufactured and will at the same time be operable and efficient in their operation.

The above and additional objects are accomplished by such means as are illustrated in the accompanying drawings, described in the following specification and then more particularly pointed out in the claim which is appended hereto and forms a part of this application.

With reference to the drawings, wherein I have illustrated the preferred embodiment of my invention as it is reduced to practice, and throughout the several views of which similar reference numerals designate corresponding parts: Figure 1 is a front elevation illustrating the rack in its raised position; Fig. 2 is a side elevation; Fig. 3 is a top plan view of the rack proper; and Fig. 4 is a detail view of the keeper plate employed in holding the cable of this device in its various adjusted positions.

Proceeding now to the description of the drawings, this invention includes three main elements, the clothes rack proper, the supporting and adjusting structure therefor, and the keeper plate employed in holding the rack at various elevations. Taking up these three elements in the order named, the clothes

rack proper, illustrated in detail in Fig. 3, includes a pair of side bars 1 and 2, arranged in spaced parallel relation to each other and connected by a plurality of cross rods 3. The members 1, 2 and 3 may be made of wood or any other similar and suitable material, although the preferred embodiment of this invention comprehends the utilization of light iron rods. As a means for suspending the rack from a cable, which will be hereinafter described, there are provided the four upwardly, inwardly and angularly extending attaching rods 4, arranged in the nature of the edges of a pyramid and connected at their upper terminals by a metallic plate 5 provided with a centrally arranged aperture 6, or any other suitable fastening means adapted to receive the free end of the hoisting cable. The plate 5 is also formed with a substantially square opening 7, for a purpose to be hereinafter described.

Coming now to the description of the supporting and adjusting structure, this feature of the invention includes a depending vertically arranged supporting standard 8, secured to the ceiling 9 by a plate 10, having the depending spaced plates 11 adapted to receive between their opposed faces the upper end of the member 8 and to hold it in fixed relation therebetween by means of bolt screws or rivets 12. The plate 10 may be attached to the ceiling by similar fastening means 13. The upper terminal of the member 8 is spaced from the plate 10 to provide a receiving space for pulley 14, provided with the usual pin 15 journaled in the apertures formed in the plate 11. A flexible cable 16 plays through the pulley 14 and is secured at one terminal to the plate 5 by the tying of a knot 17, as illustrated in the drawings, to prevent the withdrawal of the cable through the opening 6. In this connection it is to be observed that a ring eyelet or any other suitable fastening means may be employed in securing the cable to the plate 5. On the lower terminal of the member 8 is secured a keeper plate 18, which may be formed of sheet metal and is preferably S-shaped, being bent at each terminal as at 19 and 20 to produce this conformation. The downwardly bent terminal 20 is bifurcated to produce the tines 21, as illustrated in Fig. 1. The lower portion of the cable 16 is knotted, as at 22, 23 and 24, and carries at the extreme terminal a ball member 25,

which may be made of rubber or any other inexpensive material. In the assembled relation of the various parts of this device, the member 8 operates through the opening 7 of the plate 5 and between the rods 3 adjacent therbeneath. As to the manipulation of the structure in raising and lowering the rack, and holding it in adjusted position, it will be readily observed that by disengaging one of the knots 23 from the plate 18 the rack may be raised or lowered and held at the desired elevation by again passing the cable between the tines 21, with one of the knots 22, 23, 24, or ball 25, in engagement with the under portions thereof. It is desirable to emphasize the fact that by mounting the plate 5 for a sliding movement on the member 8, any swinging movement of the rack proper is prevented.

In reduction to practice, I have found that the form of my invention, illustrated in the drawings and referred to in the above description, as the preferred embodiment, is the most efficient and practical; yet, realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claim.

What is claimed is:

A clothes drying rack comprising a pair of parallel side bars, a plurality of cross rods connecting the side bars, upwardly and inwardly extending rods attached to said side bars, a plate secured to the free ends of the upwardly and inwardly extending rods, said plate having a central aperture and a square opening near one end, said opening being in parallel relation to the central aperture, a vertical standard, an attaching plate, said plate being adapted to secure said standard to a ceiling, a pair of spaced parallel depending arms carried by said plate and secured to said standard at its upper end, the standard being arranged to extend through the square opening in the plate, a pulley mounted between said spaced depending arms, a cable operating over said pulley, one end of said cable extending through the central opening in the plate and being secured therein, providing means for raising and lowering the rack on the standard, a keeper plate carried by the lower end of said standard and coöperating with the free terminal of the cable in holding the rack in its adjusted position.

In testimony whereof I affix my signature in presence of two witnesses.

RUDOLF AUGUST SCHIMANSKI.
